CLAIM

The ornamental design for a computer display system or portion thereof showing an animated graphical user interface having a three dimensional appearance as shown and described.

DESCRIPTION

The file of this patent contains at least one figure executed in color. Copies of this patent in color will be provided by the Office upon request and payment of the necessary fee. FIG. 1 is a front view of a computer display system or portion thereof showing an animated graphical user interface having a three-dimensional appearance showing a first image of the claimed design;

FIG. 2 is second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The peripheral dashed broken lines in the figures show the computer display system or portion thereof, and form no part of the claimed design.

The other dashed broken lines show a three dimensional environment within a field of view of the user that form no part of the claimed design.

The dot-dashed broken lines show boundaries that form no part of the claimed design.

The appearance of the animated image sequentially transitions between the images shown in FIGS. 1-7. The process or period in which one image transitions to another forms no part of the claimed design.
